FREEZEPROOF EXPANSION VALVE

George Mettler, Union City, N. J., assignor of
one-third to Magnus Bjorndal, Weehawken,
N. J.

Application October 25, 1951, Serial No. 253,121

3 Claims. (Cl. 62—127)

1
This invention relates to improvements in expansion valves for use in refrigeration and air conditioning systems, and specifically it refers to improved freeze proof, moisture separating expansion valves, which may be used instead of the so called capillary tubes widely used in commercial installations.

This invention is an improvement over my Patent Number 2,534,874 issued on December 19, 1950.

Expansion valves and capillaries have one difficulty in common, namely that if any moisture is present in the system, this will freeze up at the point where expansion takes place and will eventually clog up the valve or capillary. This can cause a great deal of costly service work and may also cause the spoilage of food products stored. As stated in my patent mention supra, the freezing up of expansion valves can be eliminated by the use of a moisture separator, such as there described. This however, requires an expensive valve and I have therefore, improved my moisture separator so that I can dispense with the valve.

The present invention therefore, is a device which combines a simplified valve with features of my previous moisture separator, thereby making it possible to eliminate capillary tubes as well as more expensive valves. This combined valve and the moisture separator eliminates all the difficulties mentioned above, and presents a unit of low cost, high efficiency and long lasting quality.

The object of my invention is to provide a freeze proof expansion valve for the use in refrigeration and air conditioning systems.

Another object of my invention is to provide a combined expansion valve and moisture separator which can be used instead of capillary tubes.

Still another object of my invention is to provide a freeze proof expansion valve which can be manufactured at low cost.

Other objects and advantages of my invention will be apparent from the following description and claims.

In the accompanying drawing, forming a part of this specification, and in which like numerals are employed to designate like parts throughout,

Figure 1 is a front view of a freeze proof expansion valve embodying my invention,

Figure 2 is a longitudinal partial section of the valve shown in Figure 1,

Figure 3 is a section taken along line 3—3 in Figure 2,

Figure 4 represents a section taken along line 4—4 in Figure 2,

2
Figure 5 represents a schematic diagram of a refrigeration system using my device, and,

Figure 6 represents a greatly enlarged part of the section shown in Figure 4.

In the drawings, wherein for the purpose of illustration is shown a preferred embodiment of my invention, the numeral 10 designates the outer tubular body of my valve. The tubular body 10, has a standard pipe fitting 11, at one end and a pipe fitting 12, at the other end. These fittings may be preferably soldered to the tube 10, but other methods of connecting the pipe joints are optional. The fitting 11, has an opening 13, which leads through a strainer 14, to the inner space inside of tube 10. The fitting 12, has an opening 15, at the outer end. The inside of the central opening 15, in the fitting 12, is tapped with a thread and the valve unit proper is designated by numeral 16.

20 The valve unit 16, has a central bore 17, at one end, which when screwed into fitting 12, communicates with the central hole 15 in same. The central bore 17, extends to about the middle of the unit 16, where it terminates in a transverse hole 18. Instead of a single hole, this may also be a plurality of holes. The unit 16, has screw threads along its entire outer surface of the body part, which is of slightly larger diameter than the threaded shank 19, which is screwed into fitting 12. The threaded body part is tapered slightly toward both ends and is completely covered by a flexible tubing 20, which is preferably made from neoprene or silicone rubber. A helical wire spring 21, is placed over the tubing 20. The spring 21, is wound opposite to the screw thread on the body portion of the valve 16.

An enlarged view illustrated in Figure 6, shows how the rubber tubing 20, is held tightly over the threaded portion of the valve body 16 with the inside of said tubing 20, pressing hard against the outer periphery of the screw threads on body 16. As mentioned above, the helical spring 21, is wound in the opposite direction from the screw thread on 16, thereby preventing that the wires 45 of the spring 21, may fall into the grooves formed by the threads and thus closing same. This is important in the proper operation of the unit, inasmuch as the screw threads act as a needling device or capillary tube letting through a certain amount of refrigerant.

50 In Figure 5, is schematically illustrated how the present invention fits into a refrigeration system. The usual refrigeration systems consists of a liquid receiver from which the liquified refrigerant passes through the expansion valve 16, to the evaporator where it is evaporated into

the gas state. The evaporated gas is compressed in a compressor and passed through the condenser where it again turns into liquid form. The expansion valve 16, may be placed at any point between the liquid receiver and the evaporator as illustrated.

The operation of my invention is as follows: when the unit is placed in the system as illustrated in Figure 5, with the pipe fittings 11 and 12 connected into the pipe connection from the liquid receiver to the evaporator, the liquid refrigerant enters through the opening 15, in fitting 12, and continues in through the central bore 17 to the transverse hole 18, whereupon a certain amount of the liquid refrigerant will pass through the capillary tubes formed by the screw thread on the body of valve 16, as described supra. With excess pressure the refrigerant will expand the rubber tube 20, and the spring 21, and will pass over the screw threads. The refrigerant will now escape from both ends of the rubber tube 20, and will expand into the chamber formed inside of tube 10. The refrigerant will now be partly gas and partly liquid in the chamber formed by tube 10, and will escape through strainer 14, and opening 13, into the pipe leading to the evaporator, where complete evaporation will take place. If any moisture is present in the refrigerant, this will freeze as the gas expands under the rubber tubing 20, and will form a small amount of ice here. This ice will only expand the tubing 20, but will not block the continuous passage of gas and liquid refrigerant through the screw threads and also under the ice or under the rubber tubing. After the refrigeration cycle has progressed a few times, all the moisture is frozen to ice and is collected under the rubber tube 20. The ice will remain here and will not affect the operation of the system until the same is stopped. It is then possible to take out the valve 16 and dry out same or replace it with a new one. In this manner, a system can be completely dried out and can also be kept operating for long periods of time with a slight amount of moisture without trouble.

It is to be understood that the form of my invention, herewith shown and described, is to be taken as a preferred embodiment of the same and that various changes in the shape, size and arrangement of parts, may be resorted to, with-

out departing from the spirit of my invention, or the scope of the subjoined claims.

Having thus described my invention, I claim:

1. A freeze proof expansion valve of the character described comprising a tubular housing having a central passage; a fitting fastened to said housing at one end; a strainer fastened in the central passage in said fitting; a second fitting fastened in the other end of said housing; a valve element placed inside of said housing and having a threaded shank screwed into said second fitting, said valve element comprising a threaded body having a central bore from said shank end, said central bore terminating in a transverse hole in the middle of said body; a flexible tube placed over said body in pressure contact with said threaded portion, and a helical spring wound over said flexible tube in the oposite direction of said screw thread.

2. A freeze proof expansion valve of the character described comprising a tubular housing having a central passage; a fitting fastened to said housing at one end; a strainer fastened in the central passage in said fitting; a second fitting fastened in the other end of said housing, said second fitting having an inlet opening leading to a tapped hole in the inner end; a valve element placed inside of said housing, said element having a threaded shank at one end screwed into said tapped hole in said second fitting; said valve element comprising a threaded body portion having a central bore from said shank end; said central bore terminating in a plurality of transverse holes communicating with the outside threaded body portion of said element, said transverse holes being located in the middle of said body; a resilient tube placed over said threaded body in pressure contact with said threads, and a helical spring wound over said flexible tube in the opposite direction of said screw threads.

3. A freeze proof expansion valve as described in claim 2 in which said valve element is tapered slightly toward both ends.
